Specification for Design.

Patented May 29, 1917.

Application filed March 23, 1917. Serial No. 157,028. Term of patent 3½ years.

To all whom it may concern:

Be it known that I, JOHN WAEHNER, a citizen of the United States, and a resident of the borough of Brooklyn, in the county of Kings and State of New York, residing at 193 Irving avenue, Brooklyn, New York, have invented a new, original, and ornamental Design for a Manicuring-Set Case, of which the following is a specification, reference being had to the accompanying drawing, forming part thereof.

The figure is a side view of a case for a manicuring set, showing my new design.

I claim:

The ornamental design for a manicuring set case, as shown.

JOHN WAEHNER.
